FIG. 1

FIG. 2

FIG. 3

FIG. 4

FIG. 5

FIGURE 1 is a perspective view of a container for a tape reel or similar article showing our new design;

FIGURE 2 is a top plan view thereof on a reduced scale;

FIGURE 3 is a side elevational view thereof;

FIGURE 4 is a bottom plan view thereof; and

FIGURE 5 is a fragmentary cross-sectional view on an enlarged scale along section line 5-5 in FIGURE 2.

The side not shown is the same as the side shown.

The dominant features of the design reside in the portions shown in full lines.

We claim:

The ornamental design for a container for a tape reel or similar article, substantially as shown and described.
